UNITED STATES PATENT OFFICE.

NICOLAI H. HILLER, OF CARBONDALE, PENNSYLVANIA.

COOLING APPARATUS.

Application filed January 19, 1926. Serial No. 82,199.

This invention relates to refrigerating or cooling systems in which there are employed a plurality of units through which the cooling fluid, such for instance as brine, is circulated.

The main object of my invention is to reduce the cost of piping, insulation, and labor involved in connecting up the several units to the header or manifold which supplies the units with the refrigerating fluid.

In order that there may be efficient circulation of the cooling fluid through each unit which may be the brine cell of a refrigerator, it is necessary to provide separate inlet and outlet passages for the brine cell. If the units are connected in parallel, it is necessary to have two separate headers and separate pipe connections from the unit to each. In some constructions it has been proposed to circulate the fluid through the units in series, in such case it being customary to provide two separate pipe connections from the unit to the header, and provide the header with a valve or obstruction between the two pipe connections for diverting the fluid through the cooling unit. In either construction, there is not only the cost of the two separate pipe connections and their separate insulations, but also the cost of the required careful and accurate workmanship in making the second connection after the first has been completed.

In my improved construction I secure an efficient circulation through each unit, and from a single header or manifold by means of a single pipe connection. Thus the cost of material for piping and insulation is reduced to one half, while the cost of installation is reduced to a far greater extent so far as concerns the labor involved in connecting up the unit to the header or manifold.

In the accompanying drawing, to which reference is to be had:

Fig. 1 is a somewhat diagrammatic representation of a pair of cooling units connected to a single header, and

Fig. 2 is a longitudinal section through one of the units and its connection to the header.

Although my invention may be employed in various types of circulating systems, I have illustrated it in connection with a series of refrigerators which may be supplied with brine from a single brine cooling apparatus.

In Fig. 1 I have shown a pair of refrigerators 10, each having a brine cell 11 therein,

and each brine cell connected by a pipe 12 to the header or riser 13.

My improved construction is preferably made substantially as shown in Fig. 2. The riser 13 has a T-coupling 14 therein, which is connected by a single pipe 15 to the brine cell 11. The T-coupling 14 has a transverse baffle or partition 16 serving to partially obstruct the flow through the riser. This may have an opening therethrough, or at one side thereof, so as to permit a part of the brine to flow directly through without going to the brine cell.

Within the pipe 15 there is provided a second pipe 17 which is preferably of lead, although it may be rubber hose or other form of piping or tubing. One end of this inner tube 17 extends through the baffle 16 and may be expanded therein or fixed thereto in any suitable manner, so that its end opens into the header 13 on the supply side of the baffle 16. The other end of the tube 17 extends into the brine cell and along the chamber thereof to a point spaced at a considerable distance from the end of the pipe 15. The end of the pipe 17 is also directed away from the end of the pipe 15 in such a manner, depending upon the type of the brine cell, that brine delivered through the pipe 17 will be caused to circulate through the brine cell before escaping from the latter through the pipe 15.

In making the installation it will be noted that there is only one pipe which has fluid-tight connections to the brine cell and the riser. Furthermore, the length of this pipe may vary to a slight extent, and the difference may be taken up by slight alteration in the position of the brine cell or refrigerator. The inner pipe 16 does not have fluid-tight connections at its inner end, and does not need to have its connection with the baffle 16 fluid-tight. In making the installation the exact positioning of the pipe 17 is not important, nor is its exact length. By making it of flexible material it permits of a movement of the brine cell toward or from the riser in making tight the connections at the ends of the pipe 15. Any difference in the rate of expansion of the pipes 15 and 17 does not tend to loosen any of the joints.

Although I have not shown any insulation on the header and the pipe 15, it will of course be understood that such insulation is used. With only a single pipe connected to the brine cell, the cost of material and

- labor in making the connection as well as applying the insulation, is very materially reduced, but the desired forced circulation through the brine cell is accomplished.
- 5 Although I have shown the pipe 17 concentric with the pipe 15, it will of course be understood that this is not essential, as the pipe, or a portion of it, may rest on the inner surface of the lower side of the pipe 15.
- 10 It will be noted that the partition or baffle 16 has two openings therein, one for direct flow through the header and the other for the flow through the pipe 17. The relative areas of these openings may be varied, de-
15 pending upon the relative amount of the total cooling fluid which it is desired to divert from the header through the particu-
lar brine cell. Instead of the pipe 17, I might in some cases provide the pipe 15 with
20 a longitudinally extending partition, one end of which would be connected to or engage with the partition 17 between the two holes of the latter, and the other end of which might be curved down into the brine cell or
25 otherwise formed or connected so as to effect the desired forced circulation through the brine cell. If it is desired to deflect all of the liquid through the brine cell, obviously
30 the opening shown at the left of the partition 16 in Fig. 2 might be entirely omitted. Ob-
viously if the flow through the header be in the opposite direction to that shown by the arrows, the pipe 17 will serve to withdraw brine from the brine cell, rather than
35 deliver it thereto.
- Having thus described my invention, what I claim as new and desire to secure by Letters Patent is:—
1. In combination a header, a cooling unit, 40 a single pipe connecting said header and said unit, a second pipe within said first mentioned pipe and having one end terminating in said header and the other in said cooling unit and means at the first men-
45 tioned end of the second pipe for directing into said second pipe liquid from said header, whereby liquid flows from said head-
er through said second pipe to said cooling unit, and thence back to said header through
50 said outer pipe.
  2. In combination a header, a cooling unit, 45 a single pipe connecting said header and said unit, a second pipe within said first men-
tioned pipe and having one end terminating in said header and the other in said cool-
ing unit at a point spaced from the end of

the first mentioned pipe and means at the first mentioned end of said second pipe for directing liquid from said header into one of said pipes.

3. In combination a header, a brine cell, a single pipe connecting said header and brine cell, a baffle within said header and provided with an aperture therethrough, and a second pipe within said first mentioned pipe and having one end extending through and supported by said baffle, and the opposite end disposed within said brine cell.

4. In combination a header having a T-
coupling provided with a baffle, a brine cell, 70 a pipe connecting said T-coupling and said brine cell, and a second pipe within said first mentioned pipe and having one end opening through said baffle.

5. In combination a header having a par-
tition therein provided with a pair of open-
ings, a brine cell, a pipe connecting said header and said brine cell, and a second pipe
within the first mentioned pipe and having
one end terminating within the brine cell 80
and the other end connected to one of the
openings of said baffle.

6. In combination a header having a par-
tition therein provided with a pair of open-
ings, a brine cell, a pipe connecting said header and said brine cell, and means within
said pipe for subdividing the interior of
the pipe into a pair of passages, both pas-
sages connected to said brine cell, and one
connected to one of the openings of said 90
partition.

7. In combination a header having a T-
coupling provided with a transverse parti-
tion at one side of the stem of the T, and
provided with a pair of openings therein, a 25
brine cell having a brine circulating cham-
ber, a pipe connecting said chamber and
the stem of said T-coupling, and a second
pipe extending lengthwise of the first men-
tioned pipe and within the latter, one end
of said second mentioned pipe extending
through one of the openings of said partition
and expanded therein, and the other end of
said second mentioned pipe extending down-
wardly in said brine chamber to a point 100
spaced from and directed away from the end
of said first mentioned pipe.

Signed at Carbondale in the county of Lackawanna and State of Pennsylvania this 16th day of January, A. D. 1926.

NICOLAI H. HILLER.
